(57) **CLAIM**

I claim the ornamental design for a nasal irrigation apparatus, as shown and described.

DESCRIPTION

FIG. 1 is a left side view of a nasal irrigation apparatus, showing my new design;

FIG. 2 is a front view thereof; and,

FIG. 3 is an exploded cross-sectional view taken in the direction of line 3-3 of FIG. 2.

1 Claim, 3 Drawing SheetsFIG. 1

FIG. 2

FIG. 3
